Primary Examiner — Cynthia Ramirez*(74) Attorney, Agent, or Firm* — Taft Stettinius & Hollister LLP(57) **CLAIM**

The ornamental design for a floor jack as shown and described.

DESCRIPTION

FIG. 1 is a perspective view of a floor jack showing the new design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The broken lines shown are included for the purpose of illustrating portions of the floor jack that form no part of the claim.
